OF D 15,379

DESIGN.

J. PEGEL.

CARPET.

No. 15,379.

Patented Sept. 2, 1884.

UNITED STATES PATENT OFFICE.

JULIUS PEGEL, OF PHILADELPHIA, PENNSYLVANIA, ASSIGNOR TO JOHN BROMLEY & SONS, OF SAME PLACE.

DESIGN FOR A CARPET.

SPECIFICATION forming part of Design No. 15,379, dated September 2, 1884.

Application filed July 22, 1884. Term of patent 3½ years.

To all whom it may concern.

Be it known that I, JULIUS PEGEL, a subject of the German Empire, and a resident of Philadelphia, Pennsylvania, have invented and produced a new and original Design for Carpets, &c., of which the following is a specification.

The nature of my invention is fully set forth in the accompanying illustration, to which reference is made.

What I claim as my invention is—
The design for carpets, as shown.

JULIUS PEGEL.
